Primary Examiner — Mary Shannon Malley*(74) Attorney, Agent, or Firm* — Muncy, Geissler, Olds & Lowe, PC(57) **CLAIM**

The ornamental design for an extraction cartridge, as shown and described.

DESCRIPTION

FIG. 1 is a perspective view of an extraction cartridge showing our new design;

FIG. 2 is a front view of the extraction cartridge;

FIG. 3 is a rear view of the extraction cartridge;

FIG. 4 is a left side view of the extraction cartridge;

FIG. 5 is a right side view of the extraction cartridge;

FIG. 6 is a top plan view of the extraction cartridge; and,

FIG. 7 is a bottom plan view of the extraction cartridge.

The dash-dash broken lines illustrate portions of the extraction cartridge that form no part of the claimed design. The dash-dot broken lines depict the boundaries of the claimed design, and form no part thereof. The areas in FIGS. 1, 4 and 5 enclosed by broken lines and dash-dot lines form no part of the claimed design.
